DESCRIPTION

U.S. PATENT DOCUMENTS

FIG. 1 is a perspective view of a combined disc player and radio receiver showing my new design;

D366,658 S * 1/1996 Fukutome D14/168
D379,627 S 6/1997 Takahashi
D381,983 S * 8/1997 Nagai D14/168
D421,607 S 3/2000 Hakoda
D426,224 S 6/2000 Yoneda
D427,581 S 7/2000 Hattori
D434,749 S * 12/2000 Ito et al. D14/168
D440,550 S * 4/2001 Nakano D14/168

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
